MOTEL SIGN

August C. Schoenfeld, 45555 Michigan Ave.,
Belleville, Mich. 48111

Filed June 17, 1968, Ser. No. 12,377

Term of patent 14 years

Int. Cl. D20—03

U.S. Cl. D96—12

FIG. 1

FIG. 2

FIG. 3

FIG. 1 is a front elevational view of a motel sign embodying my new design;

FIG. 2 is a side elevational view; and

FIG. 3 is a top plan view.

The undisclosed rear side is a mirror image of the front.

The broken lines are shown for illustrative purposes only.

I claim:

The ornamental design of a motel sign, substantially as shown and described.
